UNITED STATES PATENT OFFICE.

WILLIAM H. LEWIS AND ERASTUS B. BARKER, OF NEW YORK, N. Y.,
ASSIGNORS TO E. & H. T. ANTHONY & CO., OF SAME PLACE.

CASE FOR PHOTOGRAPHIC SENSITIZED PAPER.

SPECIFICATION forming part of Letters Patent No. 337,963, dated March 16, 1886.

Application filed August 19, 1885. Serial No. 174,802. (No model.)

To all whom it may concern:

Be it known that we, WILLIAM H. LEWIS and ERASTUS B. BARKER, both of the city, county, and State of New York, have invented 5 a new and Improved Case for Photographic Sensitized Paper or Tissue, of which the following is a full, clear, and exact description.

Our invention consists of a light-tight box having a light-tight passage-way for the movement of the paper sheet into or out of the box, and which is light-tight both when the sensitized sheet is wholly within the box and when it is being moved in or out of the same; and the invention comprises various constructions and combinations of parts, including a 15 roller within the box as above for carrying the sensitized sheet, and which is made capable of being operated from the exterior of the box for drawing in, out, and storing the 20 paper or sheet.

The invention also includes various other constructions and combinations of parts, whereby the efficiency of the case is very perfectly secured, substantially as hereinafter shown and 25 described.

The invention is applicable to carrying, preserving, and supplying as required all kinds of flexible sensitized tissue or paper, whether sensitized on one or both sides, and 30 whether used for making negatives or for photographic printing.

Reference is had to the accompanying drawings, which form part of this specification, like letters of reference indicating like parts 35 throughout the several figures of the drawings, and which illustrates one form or construction of the case embodying our invention.

Figure 1 represents a view in perspective of the case closed as constructed in the form 40 we prefer, said view also showing a portion of the flexible sensitized tissue or paper carried by the case as in the act of being drawn therefrom, likewise showing a key used in connection with the case detached. Fig. 2 is 45 a perspective view of the case when open; Fig. 3, a longitudinal vertical section of the case closed; Fig. 4, a back view of the same; and Fig. 5 a vertical transverse section upon the line x x in Fig. 3. Fig. 6 is a transverse 50 sectional view upon a larger scale of the roller which carries the paper, showing more es-

pecially a special construction of it for attachment of the paper to it.

The case, as shown in the drawings, is mainly made up of an oblong box or body 55 part, A, and corresponding-shaped lid part A', hinged to the box part in the rear, as at a a , and passing at its ends when being closed down within plates b b , secured to the ends of the box part. The box or case, 60 whether thus or otherwise constructed, is to be provided with a longitudinal passage-way for the movement of the paper to and from the interior of the box, and this passage-way is made light-tight in any suitable manner. One 65 method of making said passage-way light-tight, and the one which we prefer, is shown in the drawings, and may be described as follows: L is a longitudinal opening or slot in the box, the upper edge of which is fitted with 70 a packing strip or wiper, I, of soft flexible material, such as cloth, and which forms the upper lip of said passage-way. Said wiper, as for instance, when the longitudinal opening L is formed, as shown, in part by the lid 75 and in part by the body or box part of the case, may be secured in any suitable manner to the interior of the lid. Immediately below and in contact with said wiper I is a small longitudinal roller, H, which is journaled at 80 its ends in the end plates, b b , of the box. Said roller H constitutes the lower lip of the passage-way, and this roller, together with the wiper I, are so adjusted in respect to each 85 other that there is a passage-way, c, between them for the paper, which passage-way is light-tight both when the paper is introduced between the roller H and wiper I and also when the paper is wholly withdrawn from between said parts.

To prevent the access of light to the interior of the box at the lower surface of the roller H, we arrange another longitudinal wiper, J, of suitable soft material, to bear against the under side of the roller H, as shown. This 95 second wiper, J, may be attached to the interior of the box part of the case by any suitable means.

Arranged longitudinally within the box or body part A is a roller, B, which carries or 100 has wound upon it the flexible sensitized sheet or tissue C, the inner or one end of the roll or

sheet being entered down within a longitudinal recess, *d*, in the roller and engaging with pins or pointed teeth *s* therein, which project obliquely in a downward direction from one wall 5 of the recess *d* toward the other wall, whereby a firm hold is obtained for the paper without exposing it to being punctured otherwise than at its end through a single thickness, thus preventing the marring of the sheet or roll of 10 sensitive paper.

The roller *B*, which may be wood or other suitable material, is protected at its ends by ferrules *D*, which are constructed with outer tubular central necks or externally circular sockets, *e*, whereby said ferrules are also made to form journals for the roller, and by suitably shaping the interior of said sockets provision is made for introducing a key, *E*, to engage with the roller for the purpose of 20 rotating it to roll or take up the paper, either when first charging the case or in the event of more paper being drawn out than is necessary at any one time. By arranging these ferrule-journals at both ends of the roller carrying the paper, opportunity is afforded for 25 turning said roller by its key from either end of the case. Said ferrule-journals have their bearings in the plates *b b*, which thus form journal-boxes, as well as end covers to the 30 case, constructed to exclude light from entering at the end joints of the case.

To prevent the too free turning of the roller *B*, or, in other words, to throw a resistance upon it by friction, which will retard its run and 35 so facilitate the drawing out of the sensitive paper from the case in measured or desired quantities, cupped spring-washers *G* are introduced at the ends of said roller, between it and the ends of the case, thereby producing 40 an endwise pressure against the roller. The roller *H* also serves as a guide for the tissue or paper as it is drawn over said roller from the interior of the case by draft on its outer end from the side of the case having the opening *L*, to supply or measure off any desired 45 amount of paper, which is then torn off immediately in front of or close up to the guide-roller *H*, thus leaving the remainder of the paper under the close and light-tight cover of 50 the case. Furthermore, the two wipers *I J* are arranged so that the one wiper acts on the friction or guide roller *H* throughout its length to keep it clean or free from dust, and the other wiper acts on the tissue or paper 55 itself for a similar purpose, thereby preventing injury to the sensitized surface of the paper by dust collecting on it. This is in addition to the hereinbefore-described other and main function of said wipers—namely, of excluding light from the interior of the case, and which, if admitted, would destroy the usefulness of the tissue or paper for photographic 60 purposes.

To more effectually exclude the light from 65 the interior of the case when closed, the lid has not only a close fit at its ends under cover of the plates *b b*, but a tongue-and-groove fit,

as at *g*, with the box part of the case along or in line with the hinges, and the case is held close shut and friction thrown upon the wipers *I J*, roller *H*, and tissue *C*, passing over 70 said roller, by spring-buttons *K*, applied to the back of the lid *A'* and box part *A*. By suitably turning said buttons, however, as shown by dotted lines in Fig. 4, the case may 75 readily be opened when required to introduce a fresh sheet or roll of tissue, or as other circumstances may render necessary.

The case, as thus described, for storing photographic sensitive paper may be carried in 80 the pocket or elsewhere without risk of exposing said paper to light or dust, and the paper may be torn off for use in lengths of any desired size without affecting or exposing the remainder, and the case will be found 85 much more convenient in this and other respects than a portfolio carrying between its leaves detached lengths or pieces of photographic sensitive paper.

Having thus described our invention, what 90 we claim as new, and desire to secure by Letters Patent, is—

1. As an improved article of manufacture, a light-tight case for the storage and delivery of continuous rolls of photographic sensitive 95 paper or tissue, made substantially as described, the same consisting of a case adapted to contain a continuous roll of the sensitive material, and provided with a longitudinal slot having one or more flexible lips through 100 which portions of the roll of sensitive tissue may be withdrawn as desired, while access of light to the tissue remaining within the case is prevented, all as set forth.

2. In a case for storing photographic sensitive paper, the combination, with a light-tight box having a light-tight passage-way for the movement of the paper sheet into or out of the box, of a roller operated from the exterior of the box for drawing in and out the 110 paper, as set forth.

3. In a case for storing photographic sensitive paper, the combination, with the box having a passage-way for the movement of the paper sheet in and out of it, of a roller 115 for guiding said paper, and wipers made of soft and flexible material arranged to bear on said roller and on the paper passing over it, essentially as and for the purposes herein set forth.

4. In a case for storing photographic sensitive paper, the combination, with the roller *B*, of the ferrules *D*, constructed, as described, to form journals and key-holes for winding the roller, essentially as described.

5. The combination, with the box part *A* and hinged lid *A'*, of one or more spring-buttons applied to the back of the case, substantially as and for the purpose described.

6. The combination, with the paper-carrying roller *B*, constructed with a U-shaped longitudinal recess, *d*, of the teeth *s*, arranged wholly within said recess and projecting from one wall thereof toward the opposite wall,

and adapted to receive and hold the paper, as set forth.

7. The combination of the cupped spring-washers G with the roller B and box carrying said roller, essentially as and for the purpose herein set forth.

8. In a case for storing photographic sensitive paper, the combination, with the box part A and its hinged lid A', constructed with

a longitudinal opening, L, in front, of the 10 spring-buttons K, the roller B, the guide-roller H, and the wipers I J, substantially as shown and described.
